UNITED STATES PATENT OFFICE.

ISAAC A. BAUM, OF CHICAGO, ILLINOIS.

METAL BUCK FOR THICK WALLS.

Application filed May 5, 1928. Serial No. 275,432.

My invention relates to building construction and particularly to a novel buck and bead arrangement for thick walls.

It frequently happens in some types of buildings that the walls are of unusual thickness and suitable means should be provided for mounting a door or window casing therein of less width than the thickness of the wall. In plaster construction, this calls for a plaster return and my invention has particular reference to construction facilitating the mounting of a steel buck on the face of the wall opening, suitably anchoring the same and adapting the parts to the application of plaster on the two angular faces of the wall.

My invention will be more readily understood by reference to the accompanying drawing, in which—

20 Fig. 1 is a perspective sectional view showing an adaptation of my invention, and

Fig. 2 is a vertical sectional view through the construction shown in Fig. 1.

In the drawings, I have illustrated a wall 25 10 which may be of unusual thickness. On the exposed end face of the wall, I mount a rough buck of generally channel shape having a web 11, side flanges 12, plaster terminal flanges 13 and rebent plaster anchors 30 14. At spaced intervals in the channel, I mount wood blocks 15, secured by nails passing through the flanges 12 of the channels, and to the wood blocks are nailed the jamb 16 or other casing member. Molding 17 of 35 any desired form may be applied for finishing the opening.

Secured to the back face of the web 11 are clips consisting of a flat strip or web 18, the ends 19 of which are bent backwardly at 40 a right angle to embrace the sides of the wall 10. Where the application is made to an outside wall the clip will terminate substantially in the plane of the outer flange 12 of the rough buck and the staff molding will 45 be applied directly alongside the flange of the buck.

In order to facilitate the application of the necessary elements to the wall, I preferably provide corner beads consisting of 50 the bead member 20, web 21 and flange 22 directly to the end of the clips, welding the same in the position shown. The flange extends in either the two directions as shown at the right and left hand ends respectively 55 of the construction shown in Fig. 1. This construction not only facilitates of mount-

ing of the corner bead but materially stiffens and supports the clips in shipping and handling.

Preferably I strike out prongs 23 from the webs 18 of the clips to serve as means for mounting metal lath 24 on the face of the wall between the corner bead and the sides of the rough buck.

The clips will be positioned so as to overlie the joint between the layers of masonry, the mortar between the joints serving to insure a close fit of the clips with the wall.

Obviously the construction is capable of considerable modification and I do not wish to be limited except as indicated in the appended claims.

I claim:

1. In framing for thick wall construction, the combination of a channel shaped buck, 75 of less width than said wall, nailing blocks mounted therein; channel clips secured to the rear face of the buck in spaced apart relation and adapted to cooperate with said wall to hold the buck against movement 80 laterally of the wall and a corner bead secured to the clips.

2. In framing for walls, the combination of a metal rough buck of less width than the wall to which it is applied, a wood nailing block secured thereto, channel clips secured to the back of said buck in spaced apart relation, and a corner bead secured to said clips and defining a plaster receiving space on the end face of the wall between 90 the bead and the buck.

3. In framing for walls, the combination of a channel shaped metal rough buck of less width than the wall to which it is applied, a wood nailing block secured in said 95 channel thereto, channel clips secured to the back of said buck in spaced apart relation, and a corner bead secured to said clips and defining a plaster receiving space on the end face of the wall between the bead and the buck. 100

4. In framing for walls, the combination of a channel shaped rough buck having plaster terminal flanges, said buck being of less width than the wall to which it is applied, clips secured to the back of the buck and having angularly bent ends adapted to embrace the wall, and means on the clips adapted to act to secure metal lath on the end face of the wall.

In testimony whereof I have affixed my 110 signature.

ISAAC A. BAUM.
